[57] **ABSTRACT**

Batches of identical turnplates or analogous metallic workpieces are ground in an automatic machine wherein a pusher evacuates workpieces from a magazine and delivers them into the receptacle of a transfer unit which changes the orientation of such workpieces and places them between two pins of a clamping unit. The latter is mounted on a carriage which is reciprocable along a supporting table and moves the workpieces against the active surface of a cupped grinding wheel.

MACHINE FOR GRINDING OF WORKPIECES

BACKGROUND OF THE INVENTION

The present invention relates to a method of and to a machine for grinding, polishing or analogous treatment (hereinafter called grinding) of straight and/or curved surfaces on workpieces, especially on so-called turnplates. More particularly, the invention relates to improvements in automatic mechanical and/or electrolytic grinding of workpieces, especially to automatic grinding of large batches of identical workpieces normally consisting of hard metal. Such workpieces can be used as tools in machine tools for removal of material from metallic or other blanks. Material removing tools which are employed in machine tools and like automatic or semiautomatic machines must be ground and/or polished at frequent intervals. Such treatment must be carried out with a high degree of precision and, at the present time, requires considerable amounts of time as well as the use of complicated machinery which must be serviced and supervised by skilled attendants.

SUMMARY OF THE INVENTION

An object of the invention is to provide a novel and improved machine for grinding batches of metallic tools and/or other types of identical workpieces in a fully automatic way, with substantial savings in time, and with a high degree of precision.

Another object of the invention is to provide a machine according to which identical workpieces can be treated singly or in groups of two or more.

A further object of the invention is to provide a machine which is particularly suited for automatic treatment of so-called turnplates which are used for removal of material in machine tools.

Still another object of the invention is to provide an apparatus wherein all operations can be programmed to insure rapid, economical and accurate treatment of successive workpieces and which can be rapidly converted for treatment of different workpieces.

A further object of the invention is to provide an automatic apparatus for mechanical and/or electrolytic grinding of identical workpieces wherein a single grinding tool suffices to remove material from flat, convex, concave or other irregular surfaces.

Another object of the invention is to provide the grinding apparatus with novel and improved means for effecting rapid and accurate adjustments of movable parts and for controlling rapid advance, grinding feed, die-out feed and rapid retraction of workpieces to insure economical operation and satisfactory finish of treated surfaces.

The machine of the present invention is employed for mechanically and/or electrolytically grinding flat and/or uneven (concave, convex or otherwise curved) surfaces on a succession of identical workpieces, particularly the surfaces of turnplates for use in machine tools or the like. The machine provides the steps of mechanically moving at least one workpiece of the succession of identical workpieces to a first predetermined position (e.g., by means of a pusher or the like which expels workpieces from a magazine), mechanically moving the workpiece from such first position to a second predetermined position (for example, by means of a transfer device which comprises means for yieldably holding a workpiece during transfer),

mechanically clamping the workpiece in the second position (for example, between two clamping pins or the like), moving the thus clamped workpiece into engagement with the active surface of a grinding tool to remove material from at least one surface of the workpiece, disengaging the workpiece from the tool, and terminating the clamping action on the workpiece.

In accordance with another feature, the orientation of the workpiece is changed during transport from the first to second position; for example, the workpiece can be moved from a horizontal plane into a vertical plane in which it is in an optimum (second) position for engagement by the clamping pins. The orientation of the workpiece can also be changed after the workpiece assumes its second position; this can be achieved by resorting to templates or indexing means for one of the clamping pins. The workpiece may but need not rotate continuously during engagement with the active surface of the grinding tool, and the rate of feed as well as the maximum extent of movement of the workpiece against the tool can be varied in a fully automatic way by resorting to a suitable programming system.

The grinding tool preferably comprises a large-diameter hollow cylindrical portion of considerable axial length having at one of its axial ends a relatively narrow annular active surface.

The novel features which are considered as characteristic of the invention are set forth in particular in the appended claims. The improved grinding machine itself, however, both as to its construction and its mode of operation, together with additional features and advantages thereof, will be best understood upon perusal of the following detailed description of certain specific embodiments with reference to the accompanying drawing.

BRIEF DESCRIPTION OF THE DRAWING

FIG. 1 is a front elevational view of a grinding machine which embodies the invention;

FIG. 2 is a side elevational view of the grinding machine as seen from the left-hand side of FIG. 1;

FIG. 3 is an enlarged fragmentary vertical sectional view as seen in the direction of arrows from the line III-III of FIG. 2 and illustrates the carriage for the clamping unit of the grinding machine;

FIG. 4 is a horizontal sectional view as seen in the direction of arrows from the line IV-IV of FIG. 1 or 3 and illustrates the details of the clamping unit;

FIG. 5 is a fragmentary sectional view as seen in the direction of arrows from the line V-V of FIG. 4 and illustrates the means for adjusting the angular position of one of the clamping pins in the unit of FIG. 4;

FIG. 6 is an enlarged view of a detail in the structure of FIG. 4;

FIG. 7 is a fragmentary sectional view as seen in the direction of arrows from the line VII-VII of FIG. 4 and illustrates a portion of the means for moving the other clamping pin axially;

FIG. 8 is a fragmentary sectional view as seen in the direction of arrows from the line VIII-VIII of FIG. 4 or 9;

FIG. 9 is a sectional view as seen in the direction of arrows from the line IX-IX of FIG. 8;

FIG. 10 is a plan view of the magazine for workpieces and of a transfer unit which delivers workpieces from the magazine to the clamping unit of FIG. 4;

FIG. 11 is a vertical sectional view as seen in the direction of arrows from the line XI—XI of FIG. 10;

FIG. 12 is a vertical sectional view as seen in the direction of arrows from the line XII—XII of FIG. 11;

FIG. 13 is a vertical sectional view as seen in the direction of arrows from the line XIII—XIII of FIG. 11;

FIG. 14 is a horizontal sectional view of the transfer unit;

FIG. 15 is a vertical sectional view as seen in the direction of arrows from the line XV—XV of FIG. 14;

FIG. 16 is a sectional view as seen in the direction of arrows from the line XVI—XVI of FIG. 15;

FIG. 17 is a vertical sectional view as seen in the direction of arrows from the line XVII—XVII of FIG. 4 and illustrates the means for controlling the movements of the carriage for the clamping unit;

FIG. 18 is a sectional view as seen in the direction of arrows from the line XVIII—XVIII of FIG. 17;

FIG. 19 is a view of a detail as seen in the direction of arrow X in FIG. 17;

FIG. 20 is a side elevational and partly sectional view of the structure shown in FIG. 19;

FIG. 21 is an enlarged side elevational view of a receptacle in the transfer unit as seen in the direction of arrow Y in FIG. 14, a portion of the receptacle being shown in section;

FIG. 22 is a sectional view as seen in the direction of arrows from the line XXII—XXII of FIG. 21;

FIG. 23 is an enlarged fragmentary sectional view as seen in the direction of arrows from the line XXIII—XXIII of FIG. 24 and illustrates an adjustable weight which moves the carriage for the clamping unit;

FIG. 24 is a sectional view as seen in the direction of arrows from the line XXIV—XXIV of FIG. 23;

FIG. 25 is a sectional view as seen in the direction of arrows from the line XXV—XXV of FIG. 24;

FIG. 26 is a view as seen in the direction of arrow Z in FIG. 25;

FIG. 27 is a sectional view as seen in the direction of arrows from the line XXVII—XXVII of FIG. 26;

FIG. 28 is an enlarged vertical sectional view as seen in the direction of arrows from the line XXVIII—XXVIII of FIG. 1 and illustrates the drive and the oscillating means for the spindle of the grinding tool;

FIG. 29 is a view substantially as seen in the direction of arrows from the line XXIX—XXIX of FIG. 28;

FIG. 30 is a front elevational view of a workpiece which can be treated in the machine of FIGS. 1—29;

FIG. 31 is a side elevational view of the workpiece shown in FIG. 30;

FIG. 32 is a front elevational view of a second workpiece;

FIG. 33 is a side elevational view of the workpiece shown in FIG. 32;

FIG. 34 is a plan view of an arrangement which is utilized to adjust the amplitude of oscillatory movement of the carriage for the spindle shown in FIGS. 28 and 29, with certain parts shown in section;

FIG. 35 is a view as seen in the direction of arrow XY shown in FIG. 34;

FIG. 36 is an enlarged view of a detail in the left-hand portion of FIG. 4 and illustrates the means for indexing of the one clamping pin;

FIG. 37 is a view as seen from the left-hand side of FIG. 36;

FIG. 38 is a sectional view as seen in the direction of arrows from the line XXXVIII—XXXVIII of FIG. 37; and

FIG. 39 is a schematic plan view of a table for the structure shown in FIG. 4 and of means for changing the angular position of the table.

DESCRIPTION OF THE PREFERRED EMBODIMENTS

Referring first to FIGS. 30 and 31, there is shown a workpiece 1 which constitutes a turnplate and is of the type capable of being treated in the machine of the present invention, i.e., it can be subjected to an automatic electrolytic or mechanical grinding action. The workpiece 1 is of generally rectangular (square) outline and is provided with two phases or facets at each of its four corners. Each pair of facets includes a main facet 1b and a secondary facet 1a. The four elongated side faces or end faces are shown at 1c and the two main surfaces are shown at 1d, 1e. Each main facet 1b makes with the adjoining side face 1c an angle of 53 degrees and each secondary facet 1a makes with the adjoining side face 1c an angle of 15°. The plane of each main facet 1b and each side face 1c makes with the symmetry axis of the workpiece 1 a positive angle of 11°. The angle between such symmetry axis and the planes of the secondary facets 1a is 14°. The two main surfaces 1d, 1e are at least substantially parallel to each other.

FIGS. 32 and 33 illustrate a workpiece or turnplate 2 of triangular outline. The corners of this workpiece are bounded by arcuate or negative facets 2a which are parallel to the symmetry axis.

A machine for automatic precision grinding is shown in FIGS. 1—29 and 34—39. This machine will be described with reference to the treatment of workpieces 1 of the type shown in FIGS. 30 and 31.

Referring first to FIGS. 1, 2 and 10 to 12, the machine therein shown is designed for automatic electrolytic and/or mechanical grinding of workpieces having flat and/or curved surfaces. The machine comprises a magazine 3 which can accommodate a supply of stacked workpieces 1, and a withdrawing device or pusher 4 which can remove from the lower or discharge end of the magazine 3 one or more workpieces at a time. The pusher 4 is arranged to move back and forth in a substantially horizontal plane and delivers workpieces to a transfer unit 5 which is designed to move the thus received workpiece or workpieces in a direction at right angles to the direction of movement of the pusher and into a clamping or gripping unit 6 which then assumes a predetermined receiving or accepting position.

The clamping unit 6 is shown in FIG. 4. A workpiece 1 which is about to be received by the clamping unit 6 is located in a vertical plane. The elements of the clamping unit 6 engage the main surfaces 1d, 1e of the freshly transferred workpiece 1 and are indexible to change the orientation of the workpiece so as to place selected facets and/or faces of the workpiece into an optimum position for removal of material by a grinding tool 7 here shown as a cupped wheel. In addition to being indexible, the elements of the clamping unit 6 are preferably also capable of performing a rotary movement to thereby move selected arcuate facets or faces of a workpiece (e.g., the arcuate facets 2a of the work-

piece 2 shown in FIGS. 32-33) into engagement with the grinding tool. Upon completion of a grinding operation, the clamping unit 6 automatically reassumes a predetermined position in which it releases the the freshly treated workpiece or workpieces and is ready to accept one or more untreated workpieces. For the sake of simplicity, the following part of this description will refer to grinding of one workpiece at a time but it will become clear that the machine is equally capable of treating two or more workpieces in a single operation.

Referring to FIGS. 1 and 2 in detail, the grinding machine comprises a frame 8 having a pan-shaped upper portion 8a which accommodates a circular table 9 (indicated by broken lines). The table 9 supports several important assemblies of the grinding machine, including the aforementioned magazine 3, pusher 4, transfer unit 5 and clamping unit 6. A hand wheel 10 is provided to facilitate rotation of the table 9 about a vertical axis. This table is mounted at a level above a control panel 11 which is installed at the front side of the frame 8 and carries a set of knobs or like actuating members for the hydraulic system of the machine. The hydraulic system includes several cylinders which effect movements of certain parts in a manner as will be fully described hereinafter. The control elements of the hydraulic system are mounted in the lower front portion 8b of the frame 8 and are normally concealed behind a pivotable or removable door or cover 8c. The lower rear portion 8d of the frame 8 accommodates a generator serving to furnish the current which is necessary for electrolytic grinding of workpieces. The numeral 12 denotes an outlet pipe for electrolyte and the numeral 13 denotes a conduit which is connected to a suction generating device (not shown) and serves to evacuate gases and finely dispersed liquid particles. A further pipe 14 feeds electrolyte into the machine (see FIG. 2). The rear median portion 8e of the frame accommodates a carriage for the spindle of the tool 7 and a weight which is attached to a carriage for the clamping unit 6. The latter is movable with reference to the table 9.

The upper portion of the front side of the frame 8 carries a control panel 8f for switches, knobs and other actuating elements in the electronic programming system of the grinding machine. The electronic components of the programming system are installed in the rear upper portion 8g of the frame. The numeral 8h denotes a switch box located behind the portions 8e, 8g of the frame. FIGS. 1 and 2 further show light-transmitting panels 15 two of which flank the sides of the grinding station and are movable from closed to open positions in which they afford access to the table 9 and to the assemblies mounted thereon. The two side panels 15 are reciprocable along horizontal paths at right angles to the plane of FIG. 1. During treatment of workpieces 1, the panels 15 are held in closed positions so as to shield the person in charge from material which is being removed from workpieces.

The details of the magazine 3, pusher 4, means for reciprocating the pusher, and transfer unit 5 are illustrated in FIGS. 10 to 16. The magazine 3 comprises a removable upright duct 16 whose cross-sectional outline is such that it can accommodate a stack of horizontal workpieces 1. If the machine is to be used for grinding of differently configurated workpieces, the duct 16

is replaced with a duct which can store such different workpieces one above the other. The lower end portion of the duct 16 is located above a horizontal base plate 17 having an upwardly extending wall 17a. This lower end portion of the duct 16 is provided with a first opening 16b which permits passage of the pusher 4 and with a registering second opening or outlet 16a through which the pusher 4 evacuates the lowermost workpiece 1 from the magazine 3 whereby such workpiece travels along a predetermined path along the upper side of the base plate 17. The cross-sectional area of the opening 16b equals or closely approximates the cross-sectional outline of the pusher 4 and the area of the outlet opening 16a is such that it permits controlled evacuation of the lowermost workpiece 1. The outlet opening 16a is flanked by two guide members or cheeks 18a, 18b which define a horizontal path for controlled travel of the lowermost workpiece 1 toward the transfer unit 5.

The rear or outer end of the pusher 4 is secured to a reciprocable platen 19 which is movable along the upper side of a plate-like guide 20. The platen 19 is formed with a bore 19a for the smaller-diameter extension 21a of a piston rod 21 connected to a piston which is installed in a double-acting hydraulic cylinder 22. The outer side of the platen 19 (namely, the right-hand side, as viewed in FIG. 11) serves as an abutment for one end of a helical spring 23 which surrounds the extension 21a and the other end of which abuts against a retainer or washer 25. The latter abuts against an axially adjustable nut 24 on the outer end of the extension 21a. The spring 23 tends to maintain an annular shoulder 21b of the piston rod 21 in abutment with the inner side of the platen 19.

The upper side of the double-acting cylinder 22 is provided with an elongated groove 26 which is parallel to the pusher 4. The groove 26 accommodates a portion of the base plate 17, i.e., the cylinder 22 supports the duct 16 of the magazine 3. The groove 26 further accommodates a tongue 27 which is movable lengthwise of the cylinder 22 and the forward end of which carries a transfer plate 28 consisting of hard or hardened metallic material. The plate 28 serves as a platform on which a workpiece 1 rests during transport toward the transfer unit 5. A stop 29 at the inner end of the cylinder 22 serves to limit the extent of movement of the tongue 27 toward the transfer unit 5.

The rear or outer end of the tongue 27 is threaded 50 connected to an actuating rod 30 and serves as a retainer for one end of a helical spring 31 which is convoluted around the actuating rod 30 and the other end of which bears against a washer 32 abutting against an annular shoulder 33 of the rod 30. When the actuating rod 30 assumes its idle or inoperative position, the shoulder 33 is inwardly spaced from the platen 19 by a distance which corresponds to that to be covered by the pusher 4 in order to move a workpiece 1 from the duct 16 onto the platform 28. The outer end portion of the actuating rod 30 is freely slidable in a second bore 19b of the platen 19 and carries a washer 34 which normally abuts against the outer side of the platen (see FIG. 11).

The spring 31 is considerably weaker than the spring 23. Therefore, when the piston in the cylinder 22 performs a working stroke (in a direction to the left, as viewed in FIG. 10 or 11), the piston rod 21 causes the

stronger spring 23 to push the platen 19 toward the cylinder 22 whereby the pusher 4 transfers the lowermost workpiece onto the platform 28 before the platen 29 reaches and shifts the shoulder 33 on the actuating rod 30. During the next-following stage of leftward movement of the piston rod 21, the platen 19 compresses the spring 31 while the rod 30 pushes the tongue 27 lengthwise of the groove 26 and into abutment with the stop 29. This causes the platform 28 (and a workpiece 1 thereon) to advance toward the transfer unit 5. The spring 23 is compressed to a small degree when the workpiece 1 already enters the transfer unit 5 while the piston rod 21 continues to move in a direction to the left, as viewed in FIG. 10 or 11. The just described mode of operating the pusher 4 and of delivering workpieces into the transfer unit 5 insures gentle treatment and accurate guidance of workpieces.

FIGS. 11 and 13 further show an adjusting device which can change the level of the double-acting cylinder 22 and hence the level of the pusher 4, platform 28 and platen 19. The table 9 supports an upwardly extending cylindrical column 38 which is fixedly secured thereto and is provided with an axially extending tapped bore for the stem of an adjusting bolt 36 having at its upper end a knurled knob 35 which can be rotated by hand. The connection between the column 38 and table 9 comprises a diametrically extending pin 37. The stem of the bolt 36 has a ring-shaped shoulder 40 for a plate-like connector 39 which is secured to the cylinder 22. The cylinder 22 moves upwardly when the bolt 36 is rotated in a direction to lift the shoulder 40. The column 38 is further provided with a vertical groove or channel 41 (FIG. 10) for a tooth provided on the cylinder 22; the groove 41 prevents angular movements of the cylinder during rotation of the knob 35. An advantage of the just described level adjusting device is that the workpieces 1 can be transferred in an accurately determined plane and enter the transfer unit 5 in an optimum position for delivery to the clamping unit 6.

FIG. 11 further shows a detector 42 which is mounted on the guide 20 and cooperates with a signal generator 43 on the platen 19 to signal the retracted or starting position of the pusher 4. The parts 42, 43 constitute a so-called contactless initiator, i.e., they are capable of producing and transmitting signals without necessitating actual contact between them.

The details of the transfer unit 5 are illustrated in FIGS. 10, 14, 15, 16, 21 and 22. This unit comprises a receptacle or holder 44 which is movable to and from the receiving position shown in FIG. 10. In such receiving position, the receptacle 44 abuts against a stationary back support or anvil 46 mounted on the table 9. The receptacle 44 is provided with two mutually inclined internal locating surfaces 44a, 44b which abut against two side faces 1c of a properly introduced workpiece 1 and thus insure that the workpiece is held in a predetermined position of orientation during transport toward the clamping unit 6. Since the receptacle 44 is assumed to be used for transport of workpieces 1 of the type shown in FIGS. 30 and 31 (wherein the side faces 1c are disposed at right angles to each other), the locating surfaces 44a, 44b make an angle of 90°. These surfaces flank a triangular recess 44c which is normally flanked by two retaining walls or jaws 45a, 45b

mounted for pivotal movement on a pivot pin 44e provided in the receptacle 44. The jaws 45a, 45b are further coupled to each other by a post 141 so that they can turn on the pin 44e as a unit to and from the operative position shown in FIG. 22 for the jaw 45b. The median portion of the coupling post 141 extends through an elongated slot 44f of the receptacle 44 and is biased by one or more prestressed springs 47 which tend to maintain the jaws in their operative positions. The lower end portion of the spring 47 shown in FIG. 22 extends into a recess which is machined into the receptacle 44. A second transverse post 175 connects the jaws 45a, 45b at a point which is remote from the pin 44e; this post enters a notch 44g and abuts against the receptacle 44 when the jaws assume their operative positions.

As shown in FIG. 21, the jaw 45a is formed with holes 142 for median portions of spherical detent elements 48 which are biased toward the recess 44c by a leaf spring 49. When a workpiece 1 enters the recess 44c, one of its major surfaces 1d, 1e expels the elements 48 outwardly (downwardly, as viewed in FIG. 1) to stress the spring 49 whereby the latter insures that the thus inserted workpiece is held against movement with reference to the receptacle 44 during transport toward the clamping unit 6.

The bifurcated extension 44d of the receptacle 44 is secured to the flattened end portion 50a of a piston rod 50 by means of a screw 144 (FIGS. 10 and 15). The piston rod 50 is connected to a piston which is reciprocable in a double-acting hydraulic cylinder 51. The other end portion of the piston rod 50 extends beyond the cylinder 51 and carries a transversely extending pin-shaped follower 52 which extends into a helical groove 53a provided in a sleeve-like cam 53. Thus, when the piston rod 50 moves axially, it is compelled to simultaneously perform an angular movement and to change the orientation of the receptacle 44 by 90°. This moves the workpiece 1 in the recess 44c from a horizontal plane into a vertical plane. The cam 53 is secured to the body of the cylinder 51.

The cylinder 51 is mounted on a carriage 54 which is movable up and down in a vertical guide 147 (FIG. 16) provided therefor on the table 9. The plane in which the carriage 54 is movable up and down in parallel to the axis of the cylinder 51. The device for moving the carriage 54 comprises a vertical cylinder 145 mounted on the table 9 and having an upwardly extending piston rod 146 which is coupled to the carriage. A second contactless initiator including a detector 55 is provided on the carriage 54 to detect the extended position of the piston rod 50; this detector 55 may constitute a limit switch which is actuated by the pin 52 when the piston rod 50 moves in a direction to the right, as viewed in FIG. 15, and completes the turning of the workpiece 1 in the receptacle 44 through 90°. A third contactless initiator includes a detector 56 (FIG. 15) and a pin 148 on the piston rod 50; this initiator produces a signal whenever the piston rod 50 returns to the position shown in FIG. 15, i.e., whenever the receptacle 44 is ready to receive a fresh workpiece from the magazine 3. FIG. 14 illustrates still another contactless initiator including a detector 59 which is mounted on a bracket 58 (FIG. 16) and cooperates with a dished portion 57a of an adjusting device 57 to produce a signal in the upper end position of the carriage 54.

The clamping unit 6 is shown in FIG. 4. This unit comprises two coaxial clamping pins 60, 61. The pin 60 is of cylindrical shape but the pin 61 comprises a conical workengaging head 61a which enables the grinding tool 7 to treat positive turnplates. The head 61a of the clamping pin 61 tapers in a direction away from the cylindrical clamping pin 60. The common axis of the pins 60, 61 is normal to the direction of axial movement of the piston rod 50 in the transfer unit 5. The pin 60 is held against axial movement but is angularly adjustable with reference to its support. The other clamping pin 61 is freely rotatable about its axis and is mounted in an axially movable shaft 62 which is coupled with the shorter arm 63a of a two-armed lever 63 (see also FIG. 7) in such a way that it moves with the pin 61 axially in response to pivotal movement of the lever. The longer arm 63b of the lever 63 is coupled to the piston rod 64 of a hydraulic clamping cylinder 65 which is mounted on the table 9. The pivot 66 for the lever 63 is mounted in a bearing member 67 which is connected with one end of a pull rod 68. The latter is parallel with the shaft 62 and piston rod 64 and its other end is connected to the vertical wall 69a of a housing 69 which supports the cylindrical clamping pin 60 and forms part of a carriage 77 for the clamping unit 6. The housing 69 also supports the clamping cylinder 65.

The clamping pin 60 is mounted at the front end of a shaft 70 which supports a freely rotatable worm wheel 71. The latter is secured to one element 72a of an electromagnetic clutch 72 the other element 72b of which is fixedly secured to the shaft 70. As shown in FIG. 5, the worm wheel 71 meshes with a worm 73 which is mounted on the output shaft of an electric motor 74. Thus, when the clutch 72 is energized to operatively connect the elements 72a, 72b, and when the motor 74 is thereupon started, the worm 73 rotates the shaft 70 through the intermediary of the worm wheel 71 and clutch 72 to change the angular position of the clamping pin 60. As mentioned above, the pin 60 is held against axial movement. The extent of angular movement of the shaft 70 and pin 60 can be determined in advance by a suitable electric selector 75 shown in FIG. 5 and cooperating with the shaft of the motor 74.

The shaft 62 preferably serves as a conductor for electric current to the clamping pin 61. To this end, the shaft 62 carries sliding contacts 107 which are disengaged from a collector 108 (FIG. 6) when the shaft 62 rotates. An elastic current-conducting coupling 150 (FIG. 6) connects the collector 108 with the shaft 62. FIG. 6 further shows antifriction bearings 80 for the shaft 62. The shaft 70 for the cylindrical clamping pin 60 is mounted in antifriction bearings 81.

The transfer unit 5 cooperates with the clamping unit 6 in the following way:

When the cylinder 51 of FIG. 15 causes the piston rod 50 to perform a working stroke during which the pin 52 moves toward registry with the detector 55, the workpiece 1 in the recess 44c of the receptacle 44 is turned through 90° and comes to rest in a vertical plane at a level below the pins 60, 61 of the clamping unit 6. In the next step, the cylinder 145 (FIGS. 15 and 16) is actuated to move the cylinder 51 and piston rod 50 upwardly whereby the workpiece 1 enters the space between the pins 60, 61. During upward movement of a workpiece 1 and the receptacle 44, the pins 60, 61

respectively engage the jaws 45a, 45b of the transfer unit 5 and pivot such jaws against the opposition of the spring 47 (FIG. 22) whereby the detent elements 48 release the workpiece. The upward movement of the receptacle 44 is terminated when the axis of the workpiece 1 coincides with the common axis of the clamping pins 60, 61. In the next step, the cylinder 65 causes the lever 63 to move the shaft 62 and pin 61 axially toward the pin 60 so that the workpiece 1 is securely clamped between the pins 60, 61. The automatic grinding operation can begin as soon as the receptacle 44 descends (in response to actuation of the cylinder 145), and the exact nature of such grinding operation depends on the setting of the programming system.

In the meantime, the receptacle 44 returns to the receiving position of FIG. 11 (in response to actuation of the cylinder 51) and is ready to accept a fresh workpiece.

The housing 69 for the shafts 62, 70 of the clamping pins 60, 61 forms part of the aforementioned carriage 77 (FIG. 3) which is movable with reference to the table 9 along a horizontal path at right angles to the common axis of the clamping pins 60, 61. The shaft 70 carries a pattern or template 76 (FIGS. 4 and 8) which can move into abutment with a ruler 78 mounted on the table 9 by way of an adjusting device 79 (FIG. 4). The aforementioned antifriction bearings 81 are adjustable to hold the shaft 70 without any appreciable play.

The outer end portion of the shaft 70 carries a large-diameter index wheel 82 which cooperates with an adjustable arresting member 83 (FIG. 37) to hold the shaft 70 in accurately determined angular positions. The member 83 fixes the angular position of the clamping pin 60 when the shaft 70 is idle. Precision adjustments in selected position of the shaft 70 can be effected by means of an eccentric 84 which engages the arresting member 83 and can move the latter substantially tangentially of the index wheel 82. In the illustrated embodiment, the wheel 82 is a functional equivalent of a spur gear.

The carriage 77 for the clamping pins 60, 61 is movable toward the grinding tool 7 under the action of a weight 86 (FIGS. 23-25). The speed of movement of the carriage 77 is controlled by a hydraulic cylinder 87 (FIG. 4) which is mounted on the table 9 and has a piston rod 88 abutting against the carriage 77. The cylinder 87 also serves as a means for moving the carriage 77 in a direction to move the pins 60, 61 away from the grinding tool 7, as well as to one or more predetermined intermediate positions (see FIGS. 4 and 17). FIG. 17 shows that the support for the cylinder 87 carries elastic cushions 89 which engage the carriage 77 in its starting or retracted position and which cushion the last stage of return movement of the carriage toward such position. The cushions 89 store at least some energy in the starting position of the carriage 77 and transmit to the carriage a starting impulse when the carriage begins to move in a direction to advance the pins 60, 61 toward the grinding tool 7. The controls for the cylinder 87 are adjusted in such a way that the piston rod 88 rapidly leaves its retracted position to move the carriage 77 to a receiving position in which the clamping unit 6 accepts a fresh workpiece 1 from the transfer unit 5. The piston rod 88 is thereupon

rapidly retracted to a position in which the workpiece between the pins 60, 61 is immediately adjacent to the active surface 7a of the grinding tool 7. The controls for the cylinder 87 thereupon reduce the speed of the piston rod 88 to insure gradual engagement between the workpiece and the active surface 7a (FIGS. 3 and 4).

As shown in FIGS. 4 and 17, the table 9 further supports an indexable stop cam 90 which is biased axially by a package of dished springs 100. FIG. 19 shows that the exposed face of the cam 90 carries several angularly spaced lobes 90a, 90b, 90c, 90d of different height (as considered in the axial direction of the cam 90 and piston rod 88). A selected one of these lobes can be moved into registry with a projection 91 on the carriage 77. The lobes 90a-90d are further provided with radially outwardly extending studs 92 adapted to cooperate with a detector 93 to thus signal the selected angular position of the cam 90. The purpose of the lobes 90a-90d is to determine the extent of feed movement of the carriage 77. One of the lobes 90a-90d is further provided with a second stud 94 (FIG. 17) which cooperates with a further detector serving to signal the initial or zero position of the cam 90. The detectors and the associated studs form part of contactless initiators of the aforescribed type.

The means for indexing the cam 90 comprises a rack 97 (FIG. 18) which is reciprocable by the piston rod 95 of a hydraulic cylinder 96 and meshes with a pinion 98 on the shaft of the cam 90. The connection between the cam 90 and the pinion 98 includes a one-way clutch 99 (FIG. 17) which enables the rack 97 to turn the cam 90 in one direction. The cam 90 terminates the feed movement of the carriage 77 during grinding of flat surfaces, such as the side faces 1c of the workpiece 1 shown in FIGS. 30 and 31. The grinding of curved surfaces (such as the facets 2a of the workpiece 2 shown in FIGS. 32 and 33) is controlled by the template 76 and ruler 78.

The projection 91 is movable axially of the cam 90 by means of a micrometer screw 101 shown in FIGS. 4 and 17. Furthermore, the projection 91 carries the sensing element 102 of a pressure gauge 103. This sensing element 102 can be engaged by the selected lobe on the cam 90 when the carriage 77 completes its feed movement. The gauge 103 then produces a signal which initiates the final mechanical grinding operation and, if necessary, arrests the generator to thus terminate the electrolytic grinding operation.

The starting position of the carriage 77 is determined by a further stop 104 (FIG. 17) which can engage a flange 105. The latter is adjustable axially by a screw 106 which is provided with a fine thread and meshes with the carriage 77. The stop 104 is mounted on the table 9.

As shown in FIG. 28, the grinding tool 7 is a cupped body of very large diameter and of substantial depth. The active surface 7a of this tool is the narrow annular surface of a large-diameter cylindrical front portion 7b having a relatively small thickness (as measured radially of the tool). The internal diameter of the cylindrical portion 7b is large enough to accommodate that part of the carriage 77 which supports the shaft 62 for the clamping pin 61 (see FIG. 4). This is necessary when the machine is used for grinding of positive turnplates such as the plate 1 of FIGS. 30 and 31.

The speed of feed movement of the carriage 77 can be regulated by automatic adjustment of the weight 86 (FIGS. 23 to 27). To this end, the carriage 77 is connected with one end of a flexible element 151 (hereinafter called cable) which is trained over pulleys 152, 153. The other end of the cable 151 is connected with the upper end of a vertically movable supporting bar 109. This bar carries two sets of disk-shaped weights 110 and 110a. Each of the weights 110 has a central opening for and is slidable along the bar 109. For example, each of the heavier weights 110 can weigh 40 kilograms. The bar 109 has a fixed collar 112 on which the lowermost weight 110 rests by gravity and the other weights 110 rest on such lowermost weight. The collar 112 is located at a level above a plate-like carrier 113 which is welded to a casing 155. The bar 109 extends through the carrier 113 and its lower end portion is provided with a second collar 154 for the lighter weights 110a; each of these weights can weight 10 kilograms.

The carrier 113 supports blocking or intercepting members 111 which are equidistantly spaced about the bar 109 and are pivotable on pins 114 which are parallel to the bar 109. The free end of each intercepting member 111 is articulately coupled to a link 115 and each link is articulately coupled to a turntable 116. The latter is mounted below the carrier 113 and is coupled (as at 149) to the outer end of a piston rod 117 which is reciprocable by a double-acting hydraulic cylinder 118. The cylinder 118 is articulately connected to the carrier 113 by a pivot pin 156. The members 111 can either intercept or be moved away from the path of downward movement of the heavier weights 110 so that the operator of the machine can select the force with which the carriage 77 is advanced while the workpiece between the clamping pins 60, 61 contacts the active surface 7a of the grinding tool 7. Thus, the members 111 will be caused to intercept the heavier weights 110 when the tool 7 is to remove material from relatively small surfaces on a workpiece but the members 111 will permit the carriage 77 to feed the workpiece against the tool with a greater force (determined by the combined mass of the weights 110 and 110a) when the tool is to remove material from a relatively large surface.

The extent to which the table 9 is turnable about its vertical axis is determined by adjustable stops 119 shown in FIG. 39. These stops cooperate with a projection 9a of the table 9; the latter is further provided with an index which moves with reference to a stationary scale on the frame 8. The means for turning the table 9 comprises a double-acting hydraulic cylinder 121 whose piston rod 120 is articulately connected to a portion of the table. The machine further comprises clamping means (not shown) for fixing the table 9 in selected angular position.

FIGS. 28 and 29 show that the grinding tool 7 is mounted on a hollow spindle 122 preferably having a very large diameter so as to exhibit a highly satisfactory static and dynamic rigidity. That end of the spindle 122 which is remote from the tool 7 carries a pulley 123 whose front face is provided with a collector ring 124. This collector ring 124 cooperates with spring-biased contacts 125 extending in parallelism with the spindle 122. The spindle 122 is mounted in a carriage 126 by

means of insulators 157 and this carriage is movable along ways 160 in a horizontal plane at right angles to the axis of the spindle. The pulley 123 is driven by a pulley 158 through the intermediary of a flat belt 127. The pulley 158 is mounted on the output shaft of an electric motor 159. The means for moving the carriage 126 back and forth along the ways 160 comprises a double-acting hydraulic cylinder 132. The flow of fluid to and from the chambers of the cylinder 132 is adjustable in such a way that the cylinder can impart to the revolving tool 7 rapid oscillatory movements of short amplitude or slower oscillatory movement of maximum amplitude while the active surface 7a engages a workpiece which is held between the clamping pins 60 and 61. It is clear that the double-acting cylinder 132 can be replaced with a crank drive or other suitable means for oscillating the spindle 122 and tool 7.

The housing 181 shown in FIG. 28 shields the spindle 122, carriage 126 and certain other parts from splashing liquid.

As shown in FIGS. 34 and 35, the upper part of the bearing block 161 for the spindle 122 of the tool 7 carries a set of three detectors 133 in the form of contactless limit switches which cooperate with conical disks 134, 135 and a ruler 136. The parts 134, 135, 136 are mounted on adjusting rods 162, 163, 164 which are movable axially with reference to a supporting bracket 165 and a wall member 166. The rods 162-164 are provided with pairs of axially movable flanges 167 which flank the bracket 165. One flange 167 of each such pair abuts against the adjacent surface of the bracket 165 under the action of a package of dished springs 168. Each package of springs 168 reacts against one flange 167 of the respective pair and urges the other flange against the bracket 165. The extent to which the flanges 167 of each pair are movable away from each other is determined by radially extending pins 169 fixed to the rods 162, 163, 164.

The right-hand end portions of the rods 162-164 are surrounded by sleeves 171 which are secured thereto by pins 172. The sleeves 171 are secured to cruciform knobs 180 by means of pins 170. Each pin 172 extends radially beyond the respective sleeve 171 which latter is provided with an axially parallel slot 173. The outermost parts of the pins 172 can engage arresting posts 174 or 174a which are mounted on the wall 166 and extend in parallelism with the rods 162-164. Each post 174 is located diametrically opposite the associated post 174a.

The purpose of the rods 162, 163 and disks 134, 135 is to adjust the amplitude of oscillatory movements of the carriage 126 for the spindle 122 and tool 7. Thus, the operator can change the amplitude of oscillatory movement while the machine is in operation, for example, during deep grinding of a workpiece.

The rod 164 and ruler 136 can adjust the median position of the carriage 126.

The exact construction of the conveyor system or receptacle which receives finished workpieces 1 from the clamping unit 6 forms no part of the present invention. It suffices to say that, when the grinding of a workpiece is completed, the carriage 77 is caused to move to fully retracted or starting position in which the cushions 89 (FIG. 17) store energy, the clamping

cylinder 65 (FIG. 4) thereupon moves the clamping pin 61 away from the clamping pin 60 so that the finished workpiece is released and can descend by gravity or is taken over by a suitable transfer device, and the carriage 77 thereupon moves to an intermediate or receiving position in which it can receive a fresh workpiece 1 in response to actuation of the cylinder 145 (FIG. 15) which moves the receptacle 44 of the transfer unit 5 upwardly to place the workpiece into the space between the pins 60, 61. The cylinder 65 thereupon causes the pin 61 to clampingly engage the freshly admitted workpiece and the carriage 77 moves such workpiece toward the grinding tool 7 as soon as the receptacle 44 is moved out of the way, i.e., as soon as the cylinder 145 causes its piston rod 146 to move the carriage 54 downwardly.

Without further analysis, the foregoing will so fully reveal the gist of the present invention that others can, by applying current knowledge, readily adapt it for various applications without omitting features which fairly constitute essential characteristics of the generic and specific aspects of our contribution to the art and, therefore, such adaptations should and are intended to be comprehended within the meaning and range of equivalence of the claims.

What is claimed as new and desired to be protected by Letters Patent is set forth in the appended claims.

1. In a machine for grinding of a succession of identical workpieces, a combination comprising a magazine arranged to contain a supply of workpieces and having an outlet for workpieces; a withdrawing device operative to evacuate through said outlet at least one workpiece at a time and to advance such workpiece along a predetermined path; a transfer unit including a receptacle movable between a first position in which it receives the workpiece from said withdrawing device and a second position, and means for moving said receptacle between such positions; a clamping unit including two coaxial clamping members movable together to and from a receiving position in which they flank a workpiece in said receptacle in the second position thereof, means for moving one of said clamping members toward and away from the other clamping member to respectively grip and release the workpiece therebetween, and a carriage for moving said clamping members to and from said receiving position; and a grinding tool positioned to remove, in response to movement of said carriage, material from a workpiece which is gripped by said clamping members.

2. The machine as defined in claim 1, wherein said withdrawing means comprises a reciprocable pusher and the means for moving said receptacle comprises double-acting fluid-operated cylinder means, said carriage being arranged to move at right angles to the common axis of said clamping members and said tool comprising a rotary grinding wheel.

3. The machine as defined in claim 2, further comprising a common support for said magazine, said carriage, said transfer unit, said withdrawing means and said tool.

4. The machine as defined in claim 1, wherein said withdrawing means includes a reciprocable pusher and further comprising means for reciprocating said pusher including a platen secured to said pusher, a double-acting cylinder having a piston rod including a portion ex-

tending through and beyond said platen, and resilient means bearing against said portion of said piston rod and reacting against said platen to thereby tend to move said piston rod outwardly, said pusher being arranged to evacuate workpieces in response to retraction of said piston rod into said cylinder.

5. The machine as defined in claim 4, further comprising a platform adjacent to said path intermediate said outlet and said receptacle in the first position thereof to support articles which move along said path, and means for moving said platform with said pusher including an actuating rod operatively connected with said platform and arranged to share a portion of movement of said platen in response to retraction of said piston rod.

6. The machine as defined in claim 5, further comprising second resilient means arranged to oppose movement of said platform with said platen with a force which is weaker than the force of said first-mentioned resilient means.

7. The machine as defined in claim 1, further comprising means for adjusting the level of said withdrawing device.

8. The machine as defined in claim 1, further comprising a back support for said receptacle in the first position thereof.

9. The machine as defined in claim 1, wherein said receptacle is provided with a recess for workpieces and with locating surfaces bounding said recess, said transfer unit further comprising a pair of retaining jaws flanking said recess and movable in planes disposed at right angles to said locating surfaces.

10. The machine as defined in claim 9, wherein at least one of said jaws is provided with detent means for yieldably retaining workpieces in said recess.

11. The machine as defined in claim 1, further comprising means for changing the orientation of said receptacle in response to movement between said first and second positions.

12. The machine as defined in claim 11, wherein the means for moving said receptacle comprises a double-acting cylinder having a reciprocable piston rod connected with said receptacle and said means for changing the orientation of said receptacle comprises a cam and a follower secured to said piston rod and arranged to track said cam.

13. The machine as defined in claim 1, further comprising means for moving said transfer unit up and down.

14. The machine as defined in claim 13, wherein said means for moving the receptacle between said first and second positions comprises a double-acting cylinder and the means for moving said transfer unit comprises a reciprocable second carriage for said cylinder, and further comprising adjustable means for limiting the extent of movement of said second carriage.

15. The machine as defined in claim 1, wherein the means for moving said one clamping member comprises an axially reciprocable shaft coaxial with and rotatably supporting said one clamping member, a pivotably mounted lever having a shorter first arm coupled to said shaft and a longer second arm, and double-acting clamping cylinder means for pivoting said lever by way of said second arm.

16. The machine as defined in claim 15, further comprising a bearing member pivotally supporting said lever for movement about an axis which is normal to the axis of said shaft and a pull rod secured to said carriage and supporting said bearing member, said pull rod being parallel to said shaft and said cylinder means.

17. The machine as defined in claim 1, wherein said clamping unit further comprises a shaft fixedly secured to and coaxial with said other clamping member, and means for changing the angular position of said shaft.

18. The machine as defined in claim 17, wherein the means for changing the angular position of said shaft comprises a worm wheel rotatably mounted on said shaft, a motor-driven worm meshing with said worm wheel, and electromagnetic clutch means energizable to couple said worm wheel to said shaft.

19. The machine as defined in claim 18, further comprising means for selecting the extent of angular movement of said shaft.

20. The machine as defined in claim 1, further comprising a support for said carriage and means for moving said carriage in a direction to advance a workpiece which is gripped by said clamping members into engagement with said tool, including a weight attached to said carriage.

21. The machine as defined in claim 20, further comprising double-acting cylinder means for controlling the speed of movement of said carriage under the action of said weight and for moving the carriage in a direction to disengage the workpiece from the tool.

22. The machine as defined in claim 21, wherein said cylinder means is arranged to move said carriage against the opposition of said weight to a starting position and further comprising elastic cushions arranged to store energy in response to movement of said carriage to such starting position.

23. The machine as defined in claim 21, further comprising means for controlling the operation of said cylinder means so as to effect rapid advance of said carriage between said starting and receiving positions and from said receiving position in a direction to move a workpiece between said clamping members toward said tool, and to effect a relatively slow advance of said carriage in said direction to move the workpiece into engagement with the tool.

24. The machine as defined in claim 1, further comprising adjustable stop means for limiting the extent of movement of said carriage in a direction to feed a workpiece between said clamping members during engagement with said tool.

25. The machine as defined in claim 24, wherein said stop means comprises a template connected to and angularly movable with one of said clamping members and a ruler constituting an abutment for said template.

26. The machine as defined in claim 24, wherein said stop means comprises an indexible cam.

27. The machine as defined in claim 26, further comprising a support for said carriage, said cam being indexible with reference to said support and having a plurality of lobes of different height, said carriage comprising a projection which registers with a selected one of said lobes and terminates the feed movement of said carriage in response to engagement with such selected lobe.

28. The machine as defined in claim 27, further comprising means for signaling the positions of said cam.

29. The machine as defined in claim 27, further comprising means for indexing said cam.

30. The machine as defined in claim 29, wherein said means for indexing comprises a pinion, one-way clutch means coupling said cam to said pinion, a rack meshing with said pinion, and means for moving said rack.

31. The machine as defined in claim 27, wherein said projection is adjustable with reference to said carriage and further comprising means for effecting precise adjustments in the position of said projection.

32. The machine as defined in claim 27, further comprising pressure gauge means associated with said projection to produce signals in response to a predetermined pressure between said projection and the selected lobe of said cam.

33. The machine as defined in claim 1, further comprising a support for said carriage, means for moving said carriage with reference to said support between a plurality of positions including said receiving position and a starting position, and adjustable stop means for arresting the carriage in said starting position.

34. The machine as defined in claim 1, wherein said tool comprises a rotary cupped grinding wheel arranged to accommodate a portion of said carriage during removal of material from a workpiece between said clamping members.

35. The machine as defined in claim 1, wherein at least a portion of said means for moving said one clamping member consists of current-conducting material.

36. The machine as defined in claim 35, wherein said current-conducting portion includes a rotary shaft and

is provided with at least one sliding contact, and further comprising collector means disconnected from said sliding contact in response to rotation of said shaft.

37. The machine as defined in claim 36, further comprising elastic current-conducting coupling means connecting said collector means with a portion of said shaft.

38. The machine as defined in claim 1, further comprising a support for said carriage and means for moving said carriage with reference to said support including a cable connected with said carriage, a plurality of weights, and means for suspending a selected number of said weights on said cable.

39. The machine as defined in claim 38, wherein said last-mentioned means comprises a turntable and intercepting members articulately connected with said turntable to intercept some of said weights in one position of said turntable and to permit all of said weights to act on said cable in another position of said turntable.

40. The machine as defined in claim 1, further comprising a frame, a support for said carriage, said support being turnably mounted in said frame, means for changing the angular position of said support, means for limiting the extent of angular movement of said support, and means for holding the support in selected angular position.

41. The machine as defined in claim 1, wherein said grinding tool comprises a large-diameter hollow cylindrical portion of substantial axial length, said cylindrical portion having a narrow annular active surface in the region of one axial end thereof.
